UNITED STATES PATENT OFFICE.

PETER HERBERT, OF CINCINNATI, OHIO.

DESIGN FOR A TABLE.

SPECIFICATION forming part of Design No. 19,115, dated May 28, 1889.

Application filed January 14, 1889. Serial No. 296,294. Term of patent 3½ years.

To all whom it may concern:

Be it known that I, PETER HERBERT, a citizen of the United States, residing at Cincinnati, in the county of Hamilton and State of Ohio, have invented and produced a new and original Design for a Table; and I do declare the following to be a full, clear, and exact description of the same, such as will enable others skilled in the art to which it appertains to make and use the same, reference being had to the accompanying drawing, and to the letters and figures of reference marked thereon, which form a part of this specification.

My design relates to a table; and the leading features consist of a table having legs and the lower circular shelf with sockets depending from its under side, and stretchers leading from the respective sockets to the supporting-legs and inclining from within outwardly and downwardly, as specifically pointed out in the claim appended.

The accompanying drawing represents in side elevation a table embodying my design.

In the said drawing, A indicates the shelf, 25 which is of a circular form and has depending from its under side sockets a.

B indicates the stretchers, which lead from the legs C to the sockets in the shelf and incline from within outwardly and downwardly. 30

I am aware that tables have heretofore been provided with shelves beneath their tops, and therefore do not claim such, broadly.

Having described my design, what I claim is— 35

The design for a table herein shown and described, the same consisting of the table having legs C and the lower circular shelf, A, with sockets a depending from its under side, and stretchers B, leading from the respective 40 sockets to the supporting-legs and inclining from within outwardly and downwardly.

In testimony whereof I affix my signature in presence of two witnesses.

PETER HERBERT.
